UNITED STATES PATENT OFFICE.

ALEXANDER WURTS, OF PITTSBURG, PENNSYLVANIA, ASSIGNOR TO THE WESTINGHOUSE ELECTRIC COMPANY, OF SAME PLACE.

SAFETY-FUSE FOR ELECTRIC CIRCUITS.

SPECIFICATION forming part of Letters Patent No. 434,168, dated August 12, 1890.

Application filed May 12, 1890. Serial No. 351,522. (No model.)

To all whom it may concern:

Be it known that I, ALEXANDER WURTS, a citizen of the United States, residing in Pittsburgh, in the county of Allegheny and State 5 of Pennsylvania, have invented a certain new and useful Improvement in Safety-Fuses for Electric Circuits, (Case No. 401,) of which the following is a specification.

The invention relates to the class of apparatus employed for protecting electric circuits and apparatus from the injurious effect of abnormal currents.

In operating certain classes of electrical apparatus under some circumstances currents of abnormal strength are liable to flow upon the circuits, and for the protection of the apparatus it is necessary that the circuits should be interrupted when such currents flow. In case the currents increase gradually the circuits may be protected by the use of lead or alloy fuses, which melt by reason of the heat developed in them on account of the resistance which they offer to the flow of current. In the event of a short-circuit upon the generator, however, the current will increase in strength to such an extent as to form an arc between the ends of the melted fuse, and it is then necessary that some means be employed for avoiding or immediately interrupting this arc in order to protect the machine and apparatus.

To this end the present invention consists in connecting in the circuit of an electric generator a lead or alloy fuse—such as is commonly employed in electric circuits and adapted to protect the apparatus against abnormal currents within certain limits—and in series with this a second fuse responding only to currents of sufficient strength to form an arc at the first fuse. This double set of fuses may be applied to each terminal of the generator or side of the circuit, and they may be repeated at any portion of the circuit where necessary.

The accompanying drawing shows in diagram a system of circuits to which the devices are applied.

Referring to the drawing, A represents an electric generator of any suitable character, and L' L² main-line conductors leading therefrom to any suitable or desired work-circuit.

In series in the line L' there are placed two fuses B' b', and likewise two fuses B² b² are placed in series in the line L². The fuse B' consists of any usual form of lead or alloy 55 fuses, such as are commonly employed for protecting electric circuits. In series with this the second fuse b' is placed. This second fuse may be of thin iron or German-silver wire, of such cross-section, however, as to 60 convey the normal currents to supply the work-circuit without undue heating and without offering great resistance to the flow of the current. The lead fuse B' has a low melting-point and will protect the circuits and apparatus against the injurious effects due to most abnormal currents. The fuse b' is required only when exceedingly high currents are flowing—such as would cause an arc between the ends of the fuse B', which, being 70 of a soft metal, is liable to volatilize, and the vapor affords a more or less perfect conducting medium. To such currents it will respond immediately. The length of the fuse b' and its material is such as to prevent an 75 arc from forming between its ends. The fuses B² and b² are similar in construction and operation.

The fuses b' b² may be of other materials than iron or German silver, and likewise various 80 different materials may be employed for constructing the fuses B' B².

The fuse b' might be employed alone and made to respond to all currents which will operate the fuse B'; but a fuse having a high 85 melting-point may be maintained at a dangerously-high temperature for a long time without melting. The fuse B', melting at a low temperature, is therefore employed for protecting the circuit from such currents as 90 are not liable to form arcs. It should also be observed that the materials having low melting-points—such as it is necessary to employ in making the fuses B'—conduce to the formation of arcs, while those employed for the 95 fuse b' do not easily arc.

I claim as my invention—

1. The combination of a lead or alloy fuse for electric circuits having a given melting-point, and a fuse of a higher melting-point 100 connected in series therewith.
2. The combination, with an electric gener-

ator and its circuit, of a strip of fusible metal responding to currents of a given strength, and a second fuse connected in series therewith, responding only to a current of a greater strength.

5. The combination, with the poles of an electric generator, of a lead or alloy fuse and a fuse having a higher melting-point connected in series with each pole of the generator, substantially as described.

10. The combination, with the respective poles of an electric generator and its work-circuit, of a fuse having a given melting-point and a second fuse having a higher melt-

ing-point connected in series between each pole of the generator and the work-circuit.

5. A compound safety device for electric circuits, consisting of two fuses connected in series, one being formed of lead or alloy and the other being formed of German silver or 20 its equivalent.

In testimony whereof I have hereunto subscribed my name this 29th day of April, A. D. 1890.

ALEXANDER WURTS.
